(57) **CLAIM**

The ornamental design for an electronic device with animated graphical user interface, as shown and described.

DESCRIPTION

FIG. 1 is a front view of a first image in a sequence of an electronic device with animated graphical user interface, showing just the graphical user interface of FIG. 6 applied to a display screen or portion thereof;

FIG. 2 is a second image thereof;

FIG. 3 is a third image thereof;

FIG. 4 is a fourth image thereof;

FIG. 5 is a fifth image thereof; and,

FIG. 6 is a front view of an electronic device with animated graphical user interface. The animated graphical user interface designs of FIGS. 2-5 may be similarly applied thereto. The outer broken lines in FIGS. 1-5 show a display screen or portion thereof, and form no part of the claimed design. The outer broken lines in FIG. 6 show an electronic device having a display screen, and form no part of the claimed design. The remaining broken lines in all figures show portions of the animated graphical user interface that form no part of the claimed design.

The appearance of the animated image sequentially transitions between the images shown in FIGS. 1-5. The process or period in which one image transitions to another forms no part of the claimed design.
